UNITED STATES PATENT OFFICE.

JOHN WILLIAM HESS, OF KITCHENER, ONTARIO, CANADA, ASSIGNOR TO CLUETT, PEABODY & COMPANY, INC., OF TROY, NEW YORK, A CORPORATION OF NEW YORK.

FOLD-OVER COLLAR.

Application filed November 29, 1922. Serial No. 603,981.

This invention relates to improvements in fold-over collars and in the method of manufacturing such collars. The invention comprises a collar containing conjoined pieces 5 of material stiff enough for wear unstarched or lightly starched and adapted to hold its shape however laundered or finished, and having a top and band of the same or of different materials, and includes a method 10 of manufacture characterized by economic simplicity.

The invention provides for the manufacture by a few simple operations of a finished collar consisting of two principal parts, one 15 forming the top and the other the band. The fabric or fabrics from which the parts are cut may be relatively thick and heavy, or include a relatively heavy inherently stiff layer of fabric. Both parts may be cut at 20 the same time from the same piece or superposed pieces of material with a minimum of waste and a maximum of accuracy in the fitting of the parts together. One advantage of the invention is to enable a collar to 25 be produced from part-blanks having edges of like but respectively opposite curvature, such as blanks separated by a single linear cut from the same piece of material, and whether made from the same or different 30 pieces of fabric, having common or interfitting curved edges to be brought together on assembly of the collar. This line of assembled edges may define in general the usual curved fold line of the collar, and provides a joint giving the appropriate form or 35 set for such collars. But the invention includes and permits the use, if desired, of relatively coarse and inexpensive material for the band of the collar where stiffness is 40 desirable, and fabric of finer or more flexible texture for the top, where appearance must be considered primarily. The fabrics used may be any of the desirable textile or other fabrics, either plain or patterned, preferred 45 for use in a collar.

In the accompanying drawings which illustrate an embodiment of the article of the invention, and stages of its manufacture,

Figure 1 is a perspective view of a completed collar;

Figure 2 shows in elevation blanks comprising the principal parts from which the collar is constructed, the irregularly curved outer edge of the top part and the substan-

tially straight lower edge of the band part 55 being shown as finished by binding;

Figure 3 is an enlarged elevation of one end of the blank for the band shown in Fig. 2;

Figure 4 is a partial elevation of the band 60 part of the collar after edge-folding, the face of the part shown being that covered and concealed in use by the top;

Figures 5 and 6 are enlarged elevations of one end of the top shown in Fig. 2, respectively before and after creasing;

Figure 7 is a view similar to Figs. 5 and 6 of the top after edge-folding and stitching;

Figure 8 is a partial elevation of the principal blanks assembled in face-to-face 70 engagement and bound together;

Figure 9 is an enlarged sectional view on the line 9—9 on the Fig. 8;

Figure 10 is a fragmentary elevation of the inner or concealed faces of the united 75 parts of the collar showing the top flattened into the plane of the band and the uniting seam folded over upon the band part;

Figure 11 is a view similar to Fig. 10 showing a facing stitched to the tab end of 80 the band portion and the lower edge of the band completed;

Figure 12 is an elevation similar to Fig. 11 showing the bound joint stitched to the band portion of the collar, the button holes 85 made and the collar completed; and

Figure 13 is a section substantially on the line 13—13 of Fig. 12 showing the collar folded along the line of the uniting seam.

Referring now to the drawings, the principal blanks 14 for the top and 15 for the band may be cut from a sheet, sheets or laminated sheet of suitable fabric, preferably a woven textile fabric thick and heavy enough to provide the desired stiffness in 95 one thickness. For economy, the band part 15 may be made of coarser or less expensive material than top part 14, which can be of any texture preferred for good appearance; but the textural surface, weight, degree of 100 stiffness, color and fabric of the collars are variable at the desire of users, and these qualities may be those in vogue or individually preferred by the user.

The unattached edges of the top part 14 105 and the lower edge of the band part 15 are suitably finished, as by binding with a strip or tape 16 fastened and by a single row of

stitching 17 extending through the binding and the intermediate thickness of the collar material. The blanks 14 (which may be cut with rounded corners at 19, Figs. 2, 5 and 6, to enable these edges to be continuously bound and reduce the material at the corner fold) and the blanks 15 are preferably bound at 16 and 17 as the next step in making the collar after cutting out the blanks.

The band is now edge-folded, preferably by the usual machine-folding operation, to the state illustrated in Fig. 4, the entire edge of the band being folded over on the same face as indicated at 18. The edge fold is preferably not sewed at this time.

The top blank 14, Figs. 5 and 6, having been bound, Fig. 5, is creased along the lines 20 and 21, Fig. 6, crossing at the place of the finished corner within and near the rounded bound edge 19, to define a corner-fold at the proper position. The blank is first folded, for example, at the crease 20, as indicated in Fig. 7, and then is folded at crease 21, and the folded margins are secured in place by a row of stitching 22.

The parts of the collar may now be placed face-to-face as indicated in Fig. 8, the edge fold at edge 30 of the band being opened, and the edges 30 and 31 of band and top being in registry. A strip of tape or other binding 23 having selvages, or, as shown, inturned edges 24, is now applied and sewed at 25, Figs. 8 and 9, along the unfinished edges 30 and 31 of parts 14 and 15, the binding terminating at 32, Fig. 8, where it is severed close to the edge of band blank 15. This operation may be by the usual function of a sewing-machine having an over-edge binder guide and adapted to form the stitches 25 at a predetermined distance from the bound edge. The binding 23 may be and preferably is a thin flexible strip, so that the bound joint between band and top, see Fig. 9, is strong without being bulky. This joint encloses a single thickness only of the top and band portions 14 and 15 respectively.

The parts may now be laid out flat by folding the bound joint upon the band 15 along the crease 18 of the band 15 formed by the original edge-folding operation, and the ends may now be finished by attaching an infolded facing piece 26 of thin fabric by a row of stitching 27 to the projecting tabs or ends and adjacent parts of the band

15. Stitching 27 serves to retain in place the folded marginal edge portions of the band covered by it, which have not before been sewed. A second row of stitching 28 is run along the lower portion of the facing 60 and the length of the band to secure the lower edge-fold of the band in place as illustrated in Figs. 11 and 13. The bound joint 23, etc., may now be secured to the band of the collar, if desired, by a row of stitching 29 extending from one facing 26 to the other, as illustrated in Fig. 13; the button holes 32 made; and the top 14 folded along the line defined by the bound joint to the position illustrated in section in Fig. 13. The bound joint 23, 24, 25 being accurately curved and relatively stiff, predetermines the relative position or "set" of the top when the band is curved and fastened in the position of wear.

A collar made as above recommended is, see Fig. 13, characterized by a fold-line for the top of the collar of the full thickness of the material of the top bent over the thin binding 23 only, and related to the original shape of the blanks from which it is assembled without substantial deviation or error. The fold made in the top, being of the full thickness of the material, is sufficiently full for good appearance and not so full as is the case when a relatively thick top is folded over a seam or edge of thick material, or containing a large number of plies. The appearance of this edge is of critical importance to the appearance of the collar as a whole. It will be observed that the described operations assemble the collar by steps resulting in fastening down the edge-folds from time to time incident to or during other operations, such as forming of the bound joint and attachment of the facings, thus reducing the number of manufacturing operations.

I claim:

A fold-over collar having a band, and a top comprised of a blank having bound edges and rounded corners overfolded and fastened, said edges being infolded on lines crossing within and near the rounded corners, whereby to provide an angled corner-fold, said infolded edges being fastened down along said infolds.

Signed by me at Kitchener, Ontario, this 13th day of November, 1922.

JOHN WILLIAM HESS.
